[57] CLAIM

The ornamental design for a device for handling patients, as shown and described.

DESCRIPTION

FIG. 1 is a top perspective view of a device for handling patients showing my new design;

FIG. 2 is a bottom perspective view thereof;

FIG. 3 is a top perspective view of a second embodiment of a device for handling patients showing my new design;

FIG. 4 is a bottom plan view of FIG. 3;

FIG. 5 is a right side elevation view of FIG. 3;

FIG. 6 is a left side elevation view of FIG. 3;

FIG. 7 is a front elevation view of FIG. 3;

FIG. 8 is a rear elevation view of FIG. 3;

FIG. 9 is a top plan view of a third embodiment of a device for handling patients showing my new design;

FIG. 10 is a bottom plan view of FIG. 9;

FIG. 11 is a right side elevation view of FIG. 9;

FIG. 12 is a left side elevation view of FIG. 9;

FIG. 13 is a front elevation view of FIG. 9;

FIG. 14 is a rear elevation view of FIG. 9;

FIG. 15 is a top plan view of a fourth embodiment of a device for handling patients showing my new design;

FIG. 16 is a bottom plan view of FIG. 15;

FIG. 17 is a right side elevation view of FIG. 15;

FIG. 18 is a left side elevation view of FIG. 15;

FIG. 19 is a front elevation view of FIG. 15;

FIG. 20 is a rear elevation view of FIG. 15.
